UNITED STATES PATENT OFFICE.

WILLIAM H. HAWS, OF JOHNSTOWN, PENNSYLVANIA.

METALLIC RAILWAY-TIE.

1,121,832.

Specification of Letters Patent. Patented Dec. 22, 1914.

Application filed July 22, 1914. Serial No. 852,404

To all whom it may concern:

Be it known that I, WILLIAM H. HAWS, a citizen of the United States, residing at Johnstown, in the county of Cambria and State of Pennsylvania, have invented certain new and useful Improvements in Metallic Railway-Ties, of which the following is a specification.

The invention relates to improvements in metallic railway ties.

The object of the present invention is to provide a simple, practical, and efficient metallic cross tie of strong, durable, and inexpensive construction, adapted to securely hold the rails and prevent the same from either spreading or moving inwardly out of the proper gage, and equipped with means for enabling the rails, at a curve, to be readily moved inwardly to the standard adjustment when the same have become worn.

With these and other objects in view the invention consists in the construction and novel combination of parts hereinafter fully described, illustrated in the accompanying drawings, and pointed out in the claims hereto appended, it being understood that various changes in the form, proportion, size and minor details of construction, within the scope of the claims, may be resorted to without departing from the spirit or sacrificing any of the advantages of the invention.

In the drawing: Figure 1 is a side elevation, partly in section, of a metallic railway tie constructed in accordance with this invention. Fig. 2 is a plan view of a portion of the metallic cross tie. Fig. 3 is a horizontal sectional view on the line 3—3 of Fig. 1. Fig. 4 is a longitudinal sectional view of one end of the metallic cross tie, illustrating the arrangement of the parts after the rail has been adjusted inwardly. Fig. 5 is a transverse sectional view on the line 5—5 of Fig. 1. Fig. 6 is a transverse sectional view on the line 6—6 of Fig. 1. Fig. 7 is a transverse sectional view illustrating another form of rail clamp, the latter being provided with fish plate extensions. Fig. 8 is a vertical sectional view on the line 8—8 of Fig. 7. Fig. 9 is a detail sectional view on the line 9—9 of Fig. 2. Fig. 10 is a detail perspective view of the reversible transverse spacing bar or member. Fig. 11 is a detail perspective view of one of the rail clamps. Fig. 12 is a detail perspective view of one of the rail supports.

Fig. 13 is a detail perspective view of one of the cross tie clamps.

Like numerals of reference designate corresponding parts in all the figures of the drawings.

In the accompanying drawings, in which is illustrated the preferred embodiment of the invention, 1 designates a metallic cross tie, U-shaped in cross section, and composed of a horizontal bottom 2 and vertical sides 3 provided at the upper and lower edges with outwardly extending horizontal flanges 4 and 5. The cross tie may also, if desired, be equipped at its end portions with bottom plates 6, preferably located beneath the rails 7 and adapted to be embedded in the ballast and to assist in anchoring the cross tie. The bottom plate of the adjacent cross ties may, as illustrated in Fig. 5 of the drawings, be of a length to extend across the space between the said ties. These bottom plates, which can, of course, be omitted, may be constructed of any desired size to adapt the cross tie to the requirements of the road and the character of the road bed.

The rails 7, which are seated directly upon the upper flanges of the cross tie, when arranged at a curve, are adapted to be adjusted inwardly to the correct gage after they have become worn, and they are held in their adjustment by means of rail clamps 8, composed of vertical portions 9 and inwardly extending approximately horizontal top jaws 10 which project over and engage the bottom flanges of the rails. The rails are supported between the sides of the cross tie by approximately inverted U-shaped supports 11 composed of spaced vertical sides 12 and a horizontal top connecting portion 13, which has its upper face arranged in flush relation with the upper faces of the top flanges of the sides of the cross tie. The vertical sides 12 of the support 11 fit against the inner faces of the sides of the cross tie and rest upon the bottom of the latter. The support 11 is of a width less than the width of the bottom flanges of the rails, as clearly illustrated in Figs. 1 and 4 of the drawings, to permit an adjustment of the rails independently of the supports. The vertical portions of the clamps are recessed at their side edges to provide horizontally projecting lugs 14, which extend into spaced horizontal slots 15 in the sides of the cross tie, whereby the rail clamps are

slidably interlocked with the sides of the cross tie. The slots 15 are spaced a distance slightly less than the width of the rails, to correspond to the size of the support 11, in effecting the lateral adjustment of the rails, and one of the rail clamps of each set is spaced from the support 11 by a reversible transversely disposed spacing bar or member 16, extending across the space between the sides of the cross tie and provided with terminal lugs 17, which extend into the adjacent slots 15 of the sides of the cross tie. The reduction of the terminals of the transverse spacing bar or member forms shoulders 18, which fit against the inner faces of the sides of the cross tie to hold the said bar or member against movement transversely of the tie, and the reduced body portion of the bar or member extends into notches 19 formed in the vertical edges of the sides 12 of the supports, whereby the spacing bar or member 16 is interlocked with the latter. When the rails are first laid, the bottom flanges project beyond the outer edges of the supports 11 a distance, say three-eighths of an inch. This provides for a three-eighths of an inch adjustment of each rail, from the position illustrated in Fig. 1 of the accompanying drawings, to that shown in Fig. 4. In careful railroading, the rails at a curve, when they become worn three-eighths of an inch, are adjusted inwardly, and the adjustment of the rails in the present invention is designed to compensate for such wear, but the parts may be constructed to permit any desired adjustment of the rails. When the outer rail of a curve becomes worn and requires adjustment, the transverse spacing bar or member, which is interposed between the outer rail clamp and the support 11, is transferred to the inner side of the rail clamp, and the rail is then shifted inwardly, making the rails the correct gage. When the rail again becomes such as to require an adjustment, the inner rail of the curve is adjusted inwardly to correct the gage. After this, when it becomes necessary to correct the gage, the outer rail has become worn to such an extent as to require a new rail.

The rail clamps are connected by horizontal longitudinally disposed bolts 20, provided at their outer ends with nuts 21 and interlocked at their inner ends with the inner rail clamp by means of a squared portion 22 for holding the bolts against rotary movement when the nuts are being screwed on or off. The longitudinal bolts may be reinforced by transversely disposed cross tie clamps 23, consisting of a bar or piece extending across the top of the cross tie at the outer face of the vertical portion of the outer rail clamp of each set, and having its terminals bent downwardly and inwardly to form hook-shaped portions 24,

which engage with the top flanges of the sides of the cross tie. The cross tie clamps, which are adapted to prevent the sides of the cross tie from spreading, are also adapted to slide inwardly on the cross tie from the ends thereof to arrange them in position, and they are secured in their engaging position by means of wedges 25, arranged in slots 26 of the top flanges of the cross tie. The slots and the wedges are of sufficient length to permit the adjustment of the outer rail clamp from the outer position shown in Fig. 1, to the inner position shown in Fig. 4. The cross tie may also be equipped with horizontal wedges 27, arranged in the outermost slots 15 and engaging the outer end walls thereof and the adjacent rail clamps. These wedges 27 are adapted to coöperate with the cross tie clamps and the locking means thereof in holding the outer rail clamps firmly in position to prevent any spreading of the rails.

The supports 11 are adapted to form seats for insulators 28, preferably constructed of two sections, as shown, and adapted to be placed on the rails at the sides thereof. These insulators 28 may or may not be employed. The rail clamps may, as illustrated in Figs. 7 and 8 of the drawings, be provided with integral upwardly extending flanges 29 forming fish plate extensions and adapted to receive transverse bolts 30 for securing the adjacent ends of the rails together. The fish plate extensions may, of course, be of any desired size to accommodate the requisite number of connecting bolts.

What is claimed is:—

1. The combination of a cross tie having sides provided with spaced slots, a rail supported by the sides of the cross tie over the space between the slots and adjustable inwardly to take up the wear, rail clamps located at opposite sides of the rail and engaging the said slots and interlocked with the cross tie by the slots, and a reversible transverse spacing bar or member arranged in the slots at one side of the rail and spacing the adjacent clamp from the inner ends of such slots, said bar or member being adapted to be transferred to the slots of the opposite side of the rail to permit an adjustment of the latter and the rail clamps.

2. The combination of a cross tie having spaced sides, a rail supported by the sides of the cross tie and adjustable thereon, a support arranged between the sides of the cross tie and being of a width slightly less than the rail, rail engaging clamps located at opposite sides of the rail, and a reversible spacing device interposed between one of the clamps and the support and adapted to be transferred to the opposite side of the latter to permit an adjustment of the rail and the clamps.

3. The combination of a cross tie having sides provided with spaced slots, a rail supported by the sides of the cross tie over the space between the slots and adjustable on the said tie, a support of a width less than the rail arranged between the sides of the cross tie, rail clamps engaging the slots and interlocked by the same with the cross tie, and a reversible spacing bar or member also engaging the slots and interposed between the support and one of the rail clamps and adapted to be transferred to the opposite side of the support to permit an adjustment of the rail and the clamps.
5. The combination of a cross tie having sides provided with spaced slots, a support arranged between the sides of the cross tie at the space between the slots and provided with notches, rail clamps interlocked with the slots, and a reversible transverse spacing bar or member interposed between the support and one of the rail clamps and adapted to be transferred to the opposite side of the support, said spacing bar or member being provided with terminal projections to engage the slots of the tie and having a portion to engage with the notches of the support.
10. The combination of a cross tie having sides provided with spaced slots, rail clamps engaging the slots, a spacing bar or member provided with means for engaging the slots and adapted to be interposed between either rail clamp and the inner ends of the adjacent slots, and a wedge extending across the cross tie and operating in the slots thereof for engaging the adjacent rail clamp.
15. The combination of a cross tie having spaced sides, inner and outer rail clamps interlocked with the cross tie and adjustable thereon, a cross tie clamp extending across the tie and slidably interlocked with the sides thereof, and fitting against the adjacent rail clamp, and adjustable fastening means for holding the cross tie clamps against the contiguous rail clamp in any adjustment thereof.
20. The combination of a cross tie provided at the top with side flanges having slots, inner and outer rail clamps interlocked with the cross tie and adjustable thereon to permit an adjustment of a rail, a cross tie clamp extending across the tie and having terminal hooks interlocked with the side flanges thereof, and wedges operating in the slots and engaging the cross tie clamp.
25. In testimony whereof I affix my signature in presence of two witnesses.
